UNITED STATES PATENT OFFICE.

WILLIAM J. IRWIN, OF TACOMA, WASHINGTON.

TYPOGRAPHICAL MACHINE.

1,400,070.

Specification of Letters Patent. Patented Dec. 13, 1921.

Application filed December 28, 1920. Serial No. 433,704.

To all whom it may concern:

Be it known that I, WILLIAM J. IRWIN, a citizen of Canada, and a resident of the city of Tacoma, county of Pierce, State of Washington, have invented certain new and useful Improvements in Typographical Machines, of which the following is a specification.

This invention relates to improvements in machines for the composing and casting of stereotyped words or lines for printing, and has for its principal object to provide a composing and type casting machine wherein a plurality of disks, each provided peripherally with type matrices, are slidably and rotatably mounted upon a central shaft to be moved between "casting" and "set" positions and wherein mechanism is provided for the successive releasing of the disks, and other mechanism is provided for advancing them along the shaft into cooperative relation with other parts whereby a mold is formed to receive the casting metal; together with means operable by actuation of the individual members of a keyboard mechanism for selectively positioning the matrices of the different disks, after the latter are released, so that the desired words or characters will be formed in the cast slugs.

It is also an object of the invention to provide means whereby the disks may be returned to initial position after being positioned for the casting of a type slug, to be used for successive operations, and means whereby the slugs may be automatically removed from the mold.

The general objects and purposes of the machine above stated and other objects and purposes hereinafter described, are attained with improvements in mechanism, the preferred forms of which are illustrated in the accompanying drawings, wherein—

Figure 1 is an end elevation of a machine constructed according to the present invention.

Fig. 2 is a transverse, vertical section of the same, particularly illustrating the character of the matrix disks used, and the selective keyboard mechanism.

Fig. 3 is an elevation of the end of the machine opposite the end shown in Fig. 1.

Fig. 4 is a plan view of the machine;

Fig. 5 is a longitudinal vertical section particularly illustrating the disk releasing

and matrix selecting means. Also the disk re-setting means.

Fig. 6 is a sectional view showing the mold 2 in position for receiving metal for casting a type slug.

Fig. 7 is a front view of the mold box shown partly in section for better illustration.

Fig. 8 is a detail perspective showing one of the character selecting keys, a matrix 65 disk, and release and stop mechanism controlled by the key.

Fig. 9 is a detail view of the shaft rotating means.

Fig. 10 is a detail view of the retaining 70 dogs on the disk supporting shaft.

Fig. 11 is a view illustrating the means for rotating the disks after they are released.

Fig. 12 is an enlarged perspective view of 75 a portion of one of the disks.

Referring more in detail to the several views of the drawings, wherein like reference numerals designate the same or like parts—

1 designates a horizontally disposed base plate whereon all the frame structure and operating mechanism of the machine is erected. 2, 3, and 4 respectively designate the opposite end and central frame plates, 80 all of which are secured vertically in parallel relation upon the base plate, and which are joined across the front by a cross bar 5, and adjacent their rear edges by transverse brace bars 6, shown best in Fig. 3.

The central frame 4 is similar in shape to the two end frames, but differs therefrom in that it has a circular opening 7 therein through which the matrix disks 8, presently described, are shifted between set and casting positions, and through which a shaft 9, whereon the said disks are mounted and which is trunnioned at its opposite ends in the end plates 2 and 3, is concentrically and horizontally extended.

In the present construction the disks 8 are arranged face to face on the shaft 9 and are sufficient in number that a complete line can be filled thereby. In their preferred construction the disks are provided about the peripheries with equally spaced apart and radially extended character forming matrices 10, providing notches or spaces 11 therebetween, and at one side thereof have extending stop portions 12. These stop portions 110

are adapted to be moved into engagement with a cross rod 13 extended between the end frames 2 and 3, parallel with and above the shaft 9, so that the disks may be properly aligned and set for advancement by the releasing mechanism.

When in "set" position the disks are disposed on the shaft 9, as is shown in Fig. 5, at the left side of the machine, where they 10 are continuously urged toward the opposite end of the shaft by means of a spirally coiled spring 15 that surrounds the shaft and at its ends bears against the end plate 3 and against the disk pack. The disks are retained against advancement, however, except on actuation of the releasing mechanism, by means of a pair of retaining dogs 16-16' that are pivotally mounted on a slot 17 in the shaft 9 and which are yieldingly 20 held in extended position by a spring as shown in Fig. 10 to engage the face of the adjacent disk. Each disk, however, is provided at opposite sides of the central opening therein, through which the shaft 9 extends, with notches 18 which will allow the disks, when the shaft is rotated to bring the dogs in registration therewith, to pass over the latter and to be advanced along the shaft by means of the pressure exerted against the 30 disk pack by the spring 15.

It will be stated here, and it is an important feature of construction, that the notches 18 of the successive disks, when the latter are properly in "set" position, are offset angularly from each other an equal amount, so that but one disk can be released and advanced with each individual movement of the releasing mechanism. The present construction provides that the notches 18 of 40 the individual disks, when in "set" position, be offset from those of the next following disk an angular distance of sixty degrees continuing always in the same direction, so that rotating the shaft through sixty degrees after the releasing of the first disk 45 will effect the releasing of the second disk and sixty degrees more will release the third disk and so on until all are released and advanced to position for the casting of a type 50 slug.

The releasing mechanism, which is shown best in Fig. 3, comprises a lever 20, pivotally mounted at its forward end by means of a pin 21 to extend rearwardly therefrom along the outer side of the frame plate 3. This lever has a rearwardly turned arm 22 which, at its end, has attached thereto one end of a rod 23 which extends to the opposite end of the machine where it is likewise swingingly suspended by means of a link 24; this latter link being pivotally fixed to a pin 25, as shown in Fig. 1, and swings along the outside of the frame plate 1.

The rod 23 extends through slots 26 in 60 the plates 2 and 3 and horizontally through

the lower part of the machine closely beneath the arms of the key board or selecting mechanism. The selecting mechanism comprises the key arms 28 which are pivotally mounted at their inner ends on a cross rod 70 30 and which extend forwardly from the machine and at their ends are equipped with character designating keys 31. Normally these arms are held in raised position, as shown in Fig. 2, and against the cross bar 75 5 by individual springs 32 which are fixed thereto and in a cross plate 33 fixed on the base plate 1.

Pivotally fixed to the rearward end of the lever 20, Fig. 3, is a link 35 which extends 80 upwardly therefrom and at its upper end is pivotally fixed between the swinging ends of a pair of arms 36 mounted to swing pivotally on that end of the shaft 9. Mounted between these arms is a spring pressed pawl 85 37 adapted to operatively engage the teeth of a ratchet wheel 38 that is keyed onto the shaft in such manner that swinging movement of the arms 36 through a certain arc will impart rotary motion to the shaft. 90

It will be understood from the above description that the depression of any of the character selecting keys 31 will move its supporting arm 28 against the cross rod 23 to swing the latter downwardly and, through 95 the link 35, arms 36 and pawl 37 engaging with the ratchet wheel 38, to partially rotate the shaft 9. The present construction provides that the movement of the lever 20 be sufficient to cause rotation of the shaft 9 through an interval of slightly more than 100 sixty degrees with each operation of a character selecting key and that such rotation, by selective operation of the character keys, will release the disks 8 successively to be advanced to line forming position. 105

After each movement of the advancing mechanism by depression of the selecting keys, the lever 20 and associated parts are returned to normal position by means of a 110 spring 40 that is fixed at one end to the lever and at its opposite end to the frame plate 3, as shown in Fig. 3.

Successively depressing the character selecting keys not only effects the successive releasing of the disks 8, but also effects the selecting of the matrices corresponding to the keys selected, so that intelligible lines may be formed. This is carried out by the 115 following means:

Fixed to the central frame plate 4 in spaced relation thereto, is a semi-circular frame 42, and pivotally mounted between this frame and its supporting member at intervals corresponding to the angular spacing of the matrices of the disks 8, are swinging stops 43, each of which comprises an offset central portion 44 and a crank arm 45 at its end. These crank arms are connected by links 46 each with one of the 120 125 130

key arms 28 in such manner that depression of the arms will cause the stops to be swung upwardly so that the offset portions 44 thereof will be positioned adjacent the periphery of the adjacent disk 8 and in such position as to be engaged by the stop members 12 of the disks, when the latter are released and rotated on the shaft 9.

For the purpose of better explaining the function of these parts, I will assume that the first three matrices of the disks 8, as shown in Fig. 2, will respectively form the letters "a," "b" and "c." I have given these parts the reference numerals 10^a, 10^b and 10^c. Also that the first three stop members 43^a, 43^b and 43^c are controlled respectively by the character keys 31 bearing the letters "a," "b" and "c." It is apparent then that depressing the "a" character key will swing the stop 43^a outwardly and that should the disk 8 then be rotated, in the direction of the arrow, until its stop portion 12 engaged the stop 43^a, the matrix 10^a will be positioned slightly within the rod 13. It is also apparent that depression of the "c" key will likewise actuate the stop 43^c and that the "c" forming matrix of the released disk, when the latter is revolved so that its stop 12 engages the stop 43^c, will be alined with the "a" matrix of the first disk. Likewise, successively and selectively depressing any of the other keys will cause the release of the matrix disks and will arrange the matrices thereof in alinement accordingly as selected to receive the mold thereabout for the casting of a type slug.

When the disks are in "set" position, they are retained against any rotary movement on the shaft 9 by means of the rod 13 and a bar 45 fixed in the frame parallel thereto and between which the stops 12 of the disks are extended. However, as the disks are released and advanced along the shaft over the dogs 16, they are free to be rotated to bring the selected matrices into line forming position.

Rotation of the disks after they are released is automatically effected by means of a spring arm 46, Fig. 2, that is fixed, at one end, to a pivotally mounted arm 47 and at its opposite end has an inturned point 48 that seats against the forward side of the stops 12. The arm 47 is fixedly mounted on the inner end of a shaft 51 which extends revolvably through the frame plates 4 and 3 and which at its outer end has a crank arm 52 fixed thereto, Fig. 3, which is in turn connected by a link 53 to the outer ends of the arms 36; the connection being such that actuation of the arms 36 to rotate the shaft 9 to release a disk, causes rotation of the shaft 51 and downward movement of the arm 47 to throw the spring arm 46 downwardly to thereby

cause the engaged disk to be rotated to bring its stop 12 into engagement with the actuated stop 43.

Rebounding of the disks, when the stops engage each other, is prevented by the temporary seating of the stop portions 44 in notches 49, formed in the shouldered portions 50 on the rear side of the stops 12, and the selected matrices of the released disks are held in alinement, so long as the disks are in line forming arrangement, by means of a locking bar 60, Fig. 6. This bar has a loop 61 at its inner end by which it is slidably supported from the rod 13 and at its outer end extends through a slot 62 in the end plate 2 and is provided with a notch 63 adapted to receive the lower edge of the slot to lock it in position. Also, the bar is arranged parallel with the shaft 9 and in such position that as the disks 8 are advanced they will receive the inner end of the bar within the peripheral notches 11. They are advanced to locked position by the operation of a bell crank member 65, Fig. 2, that is actuated by means of a link 66 connected to a short arm thereof and to the end of the arm 47. The member 65 is pivotally mounted on the frame 4 by a pin 67 and, at the end of the longer arm, has an outwardly curved bar 68 adapted, when the arm 47 is actuated, to be projected between the released disk and the one adjacent thereto to crowd the former onto the rod end; the action being timed however so that the disk will have been rotated and stopped before being crowded onto the locking rod.

After the disks have all been advanced to form the line, a casting mold is swung thereover. The preferred mold is shown best in Figs. 2, 6 and 7 and consists of a box 70 mounted at the upper end of an arm 71. The latter is secured at its lower end to a frame 72 that is pivotally fixed to the rear of the frame members 2 and 4 and has a handle 73 fixed thereto whereby it may be actuated to swing the mold box radially against and from the alined matrices. The box is open along its lower edge to receive therein the outer ends of the matrices, Fig. 6, and at one side has an opening 75 for receiving a metal discharge tube 76 which may be moved into and from registration therewith after the mold has been actuated to casting position.

The metal used for casting the slugs is contained in a pot 80 supported from the end plate 3 and which may be heated electrically, or otherwise, to maintain the metal in a molten condition. Within the pot is a vertically disposed cylinder 81 into which the metal may flow. A pump tube 82 extends slidably through the cover of the pot, which, at its outer end, opens into a valved cup 83 and at its lower end is equipped with

a piston 84 operable downwardly within the cylinder to force charges of molten metal upwardly through the tube into the cup from which it is discharged through the 5 tube 76 into the casting box 70 to form the type slug.

The means for actuating the metal pump comprises a lever 86, that is pivotally fixed at its rearward end to the frame plate 3 and 10 extends forwardly from the machine. A link 87 connects with the lever and cup 83, at its opposite ends, in such manner that depressing the forward end of the lever will move the pump rod and piston downwardly. 15 When the lever is released, the parts are returned to neutral position by means of a spring 88 fixed at its opposite ends to the lever and to the frame plate 3, Fig. 3.

After the metal has been discharged into 20 the mold box, the latter is swung upwardly away from the matrices, to position as shown in Fig. 2, where the slug is automatically released or discharged from the box onto a receiving chute 90 along which it may slide 25 from the machine.

Pivotedly mounted within the mold is a lever 91 having an extended crank arm 92 adapted, when the mold is swung upwardly, to engage a cross bar 93 extended between 30 the frames 2 and 4 in such manner as to cause the lever to engage the slug and press it from the mold. The lever is then moved to normal position by a spring 94 as shown in Fig. 7.

35 After the line has been cast, the disks are returned to "set" position. This first requires that stops 12 of all the disks be aligned so that they may be moved along the shaft 9 between the rod 13 and bar 45. The means 40 whereby this is done consists of an arm 95 that is fixed to a rotatable disk 96 mounted concentrically about the end of the shaft 9 just within the frame end plate 2. This arm 95 has a laterally extended portion 97 overlying the disks, as shown in Fig. 2, which may be moved by rotation of the disk 96 to engage the stops 12 and move them all into alignment against the rearward side of the rod 13 so that they may then be moved 45 bodily to position as shown in Fig. 5.

The means whereby the arm is rotated and the disks moved back to set position consists of a knob 100 that is carried at the outer ends of three rods 101 which extend slidably 55 through the disk 96 and at their inner ends carry a plate 102 adapted to engage the disk pack. The knob serves as means for rotating the arm 95 and also for moving the disks to "set" position.

60 Assuming that the different parts are so constructed and assembled, operation of the machine would be as follows:

Starting with the disks in "set" position, as shown, in Fig. 5, the operation to form a 65 line of words, successively depresses the

proper character selecting keys and with the depression of each key, the shaft 9 is partially rotated, as before described, to release the forward disk from "set" position and the stop 43 connected with this particular key is actuated to stopping position. Actuation of the shaft rotating mechanism also revolves the shaft 51 to move the arm 47 to throw the spring arm 46 to rotate the stop 12 of the released disk against the stop 70 75 43 to properly position the selected matrix, and the bell crank lever 65 is actuated to move the disk onto the locking bar 60. This operation continues until the line is filled, when the mold box is moved downward to 80 receive the line of matrices as shown in Fig. 7. Depression of the lever 86 then moves the tube extended from the metal pouring cup 83 into the box opening and metal is discharged into the box to cast the slug. 85 The box is then raised to initial position and the slug is discharged into the chute 90.

The disks are then re-set by first drawing the bar 60 outwardly to release the disks for rotation on the shaft, and by turning the 90 knob 100 to cause the arm end 97 to engage and align the stops 12. The pack is then moved bodily inwardly, by inward pressure on the knob, over the yieldable dogs 16 to initial position where they are ready for 95 another similar operation.

Having thus described my invention, what I claim as new therein and desire to secure by Letters Patent, is:

1. In combination, a supporting shaft a 100 plurality of matrix disks slidably mounted on the shaft, means on the shaft for normally retaining the disks at one end thereof, a type casting mold, a key-board mechanism operable to successively release the 105 disks for advancement along the shaft across said holding means and means for advancing them into coöperative relation with said mold for the casting of a type slug.

2. In combination, a supporting shaft, a plurality of matrix disks slidably mounted on the shaft, holding means on the shaft for normally retaining the disks at one end thereof, a type casting mold, a key-board 115 mechanism operable to successively release the disks for advancement across said holding means, means for advancing them into coöperative relation with said mold for the casting of a type slug, and a re-setting mechanism for returning the disks to normal position on the shaft.

3. In combination, a supporting shaft, a plurality of matrix disks revolvably and slidably mounted on said shaft, means on 125 the shaft for normally retaining the disks at one end thereof, a spring bearing against the disks to urge them past the retaining means, a movably supported casting mold, a key-board mechanism operable to succe- 130

sively release the matrix disks for advancement along the shaft into position for receiving the casting mold thereon, means for actuating the mold against said matrix disks into position for casting a type slug and means for delivering the casting metal to the mold.

4. In combination, a supporting shaft, a plurality of matrix disks revolvably and 10 slidably mounted on said shaft, means on the shaft for normally retaining the disks at one end thereof, a spring bearing against the disks to urge them past the retaining means, a movably supported casting mold, a 15 key-board mechanism operable to successively release the matrix disks for advancement along the shaft into position for receiving the casting mold thereon, means for actuating the mold against said matrix disks 20 into position for casting a type slug, means for delivering the casting metal to the mold, and means whereby all parts may be returned to normal position after a casting operation.

5. In combination, a supporting shaft, a plurality of matrix disks rotatably and slidably mounted on the shaft; each having a like series of matrices formed peripherally thereon, a retaining means on the shaft for 30 normally holding the disks against advancement along the shaft, a spring bearing against the disks to urge them past the retaining means, a type casting mold, a key-board selecting mechanism and means operable by successive operations of selected 35 keys of the key-board for successively releasing the disks for advancement along the shaft and for rotating the same to aline the matrices thereon corresponding to the selected keys to receive the mold thereon for 40 the casting of a type slug.

6. In combination, a supporting shaft, a plurality of matrix disks rotatably and slidably mounted on the shaft; each having a like series of matrices formed peripherally thereon, a retaining means on the shaft for normally holding the disks against advancement along the shaft, a spring bearing against the disks to urge them past 50 the retaining means, a swingingly mounted casting mold, a key-board selecting mechanism, means operable by successive operation of selected keys of the key-board for releasing the disks successively for advancement along the shaft past the retaining means and for rotating them to aline the matrices thereon corresponding to the selected keys, means for actuating the mold 55 co-operatively against the alined matrices for the casting of a type slug, means for delivering casting metal into the mold and means whereby all movable parts may be returned to normal position.

7. In combination, a supporting shaft, a 65 plurality of matrix disks rotatably and

slidably mounted on the shaft; each having a like series of matrices formed peripherally thereon, a retaining means on the shaft for normally holding the disks against advancement along the shaft, a spring bearing 70 against the disks to urge them past the retaining means, a swingingly mounted casting mold, a key-board selecting mechanism, means operable by successive operation of selected keys of the key-board for releasing 75 the disks successively for advancement along the shaft past the retaining means and for rotating them to aline the matrices thereon corresponding to the selected keys, a locking bar movable into engagement with all disks 80 to retain the matrices alined, means for actuating the mold into and from co-operative relation with the alined matrices for the casting of a type slug, means for delivering casting metal into the mold when in casting 85 position, and means operable by the moving of the mold from the matrices for discharging the cast slug therefrom.

8. In combination, a rotatable supporting shaft having a retaining dog thereon, a plurality of matrix disks slidably and rotatably mounted concentrically on said shaft at one side of the dog, each having an extended peripheral stop member and a like series of peripheral matrices thereon and 90 having a notch through which said dog may pass for the advancement of the matrix disks along the shaft, a type casting mold, a spring bearing against the disks and urging them against the said dog, and, when released, into co-operative relation with the type casting mold, a key-board comprising 95 individually operable keys corresponding to the matrices of the disks, a stop member for each key operable, by movement of its key, to stopping position, means operable by the successive actuation of the keys to rotate the shaft to successively release individual disks for advancement to casting position and means for rotating each disk as it is 100 released to bring its peripheral stop portion against the key actuated stop for the purpose set forth.

9. In combination, a rotatable supporting shaft, having a retaining dog thereon, a plurality of matrix disks rotatably mounted and slidably on said shaft each having a like series of peripheral matrices thereon and having a notch therein through which the dog may pass to permit the advancement of 115 the disk along the shaft, and wherein the notch of each disk is offset a definite degree from the notch of the preceding disk, a casting mold, a spring engaging the disks to advance them along the shaft, when released, 120 into co-operative relation with the mold for casting a type slug, a key-board mechanism comprising individually operable keys and means operable by depression of the individual keys for rotating the shaft through a 125 130

definite degree to successively and individually release the disks for advancement to the casting mold.

10. In combination, a frame structure, a rotatable supporting shaft mounted in said frame, a pair of spaced alining bars mounted in the frame parallel with said shaft, a yieldable retaining dog on the shaft, a plurality of matrix disks slidably and rotatably mounted on said shaft at one side of said retaining dog, each having an extended peripheral stop member disposed between said alining bars and having a like series of peripheral matrices thereon and having a notch therein through which the dog may pass to permit the advancement of the disk along the shaft and wherein the notch of each disk is offset a definite degree from the notch of the preceding disk, a casting mold, a spring engaging the disks to advance them, when released by the dog, along the shaft into coöperative relation with said mold for casting a type slug, a key-board comprising individually operable keys corresponding to the matrices of the disks, a stop member for each key operable, by movement of its key, to stopping position, means operable by the successive actuation of the keys to rotate the shaft to successively release individual disks for advancement to casting position and means for rotating each disk as it is released to bring its peripheral stop portion against the key actuated stop for the purpose set forth.
- 35 11. In combination, a frame structure, a rotatable supporting shaft mounted in said

frame, a pair of spaced alining bars mounted in the frame parallel with said shaft, a yieldable retaining dog on the shaft, a plurality of matrix disks slidably and rotatably mounted on said shaft at one side of said retaining dog, each having an extended peripheral stop member disposed between said alining bars and having a like series of peripheral matrices thereon and having a notch therein through which the dog may pass to permit the advancement of the disk along the shaft and wherein the notch of each disk is offset a definite degree from the notch of the preceding disk, a casting mold, a spring engaging the disks to advance them, when released by the dog, along the shaft into coöperative relation with said mold for casting a type slug, a key-board comprising individually operable keys corresponding to the matrices of the disks, a stop member for each key operable, by movement of its key, to stopping position, means operable by the successive actuation of the keys to rotate the shaft to successively release individual disks for advancement, means for rotating each disk as it is released to bring its peripheral stop portion against the key actuated stop to aline the selected matrices to receive the casting mold thereon, means for re-aligning the disks on the shaft, and means for returning them to normal position back of the retaining dog.

Signed at Seattle, Washington, this 23rd day of December, 1920.

WILLIAM J. IRWIN.
